UNITED STATES PATENT OFFICE.

JOHN A. COVIT, OF NEW YORK, N. Y.

METHOD OF MAKING ELECTRIC-LIGHT STREAMERS.

1,161,454.

Specification of Letters Patent. Patented Nov. 23, 1915.

Application filed March 12, 1915. Serial No. 14,013.

To all whom it may concern:

Be it known that I, JOHN A. COVIT, a citizen of the United States, and residing at New York, in the county of New York and State of New York, have invented certain new and useful Improvements in the Method of Making Electric-Light Streamers, of which the following is a specification, such as will enable those skilled in the art to 10 which it appertains to make and use the same.

This invention relates to what are known as electric light streamers for use for decorative and other purposes, and the object 15 thereof is to provide a device or devices of this class in which the lamp sockets are hermetically sealed, and with this and other objects in view the invention consists in the method herein described of making said 20 streamers and in the article or device so produced.

The invention is fully disclosed in the following specification, of which the accompanying drawing forms a part, in which 25 the separate parts of my improvement are designated by suitable reference characters in each of the views, and in which:—

Figure 1 is a view showing a part of what is known as an ordinary electric light 30 streamer and showing a number of lamp sockets connected therewith according to my invention; Fig. 2 a section on the line 2—2 of Fig. 3; Fig. 3 a section on the line 3—3 of Fig. 2; and, Fig. 4 a section on the line 35 4—4 of Fig. 2.

In the accompanying drawing, I have shown at *a* a part of a suspending wire, wire rope or cable, such as is usually employed in constructing and using what is known as 40 electric streamers for decorative or other purposes together with the usual circuit wires or cables *b* and, in Fig. 1, I have shown a number of electric lamp sockets *c* connected with the wires or cables *b* according 45 to my invention. The sockets *c*, in the form of construction shown, consist of head portions *c*² and shank portions *c*³, and the electric light bulbs *c*⁴ are screwed into the socket devices *c* in the usual manner.

50 The sockets *c*⁵ are formed in the shank portions *c*³, in the usual manner, and are provided with threaded metal sleeves *c*⁶ and blocks *c*⁷ of porcelain or similar material through which are passed plugs or bolts *c*⁸ 55 and one of the circuit wires *b* is in electrical connection with the metal sleeves *c*⁶ and

the other with the plugs or bolts *c*⁸ as shown at *c*⁹ and *c*¹⁰ in Fig. 3, and when the lamp bulbs *c*⁴ are screwed into the socket pieces, the electric circuits through said bulbs are 60 completed in the usual manner.

The parts *c*⁶, *c*⁷, *c*⁸, *c*⁹ and *c*¹⁰ constitute the electric fittings of the sockets and in carrying my invention into effect said parts are assembled in the manner shown and are 65 connected with the circuit wires *b* and are all supported in suitable molds arranged at intervals and the material of the socket pieces, rubber, or other suitable material in a liquid or plastic state is poured into the mold 70 and placed under pressure and the body of the lamp sockets shaped or formed, as shown in the accompanying drawing, is produced and ready for use with the circuit wires *b* passing laterally therethrough and the 75 bodies of said lamp sockets are hermetically sealed, except at the bottom and no moisture of any kind or class can enter the said sockets when suspended, as shown in Figs. 80 1 to 3 inclusive.

In the foregoing method of operation the insulation of the socket wires *b* is placed thereon in the usual manner and the lamp sockets are molded on said circuit wires and the result of this operation is shown in Fig. 85 4, the molding of said lamp sockets under pressure serving to compress the insulation of the circuit wires *b*, as indicated in said figure, and this method or the result thereof also aids in hermetically sealing the lamp 90 sockets. It will be understood that streamers of this kind involving the circuit wires *b* with the lamp sockets formed thereon may be made up of sections of any desired length, and any number of said sections may be connected, and in the operation of molding the lamp sockets, as herein described, eye-pins or bolts *d* are molded in the tops of the heads *c*² and the suspending wire or cable *a* is connected therewith by means of open 95 rings, wire loops or similar devices *e*, as shown in Fig. 1.

100 My invention is also not limited to the idea of suspending the lamp sockets from the circuit wires *b*, as herein shown and described, and my improvement may be used in connection with sign boards or sign apparatus by passing the neck or shank portions of the sockets horizontally through a vertically arranged board or frame so that the lamp bulbs will appear at the front of 110 said board or frame only and in this use of

my improvement the circuit wires *b* and the heads of the lamp sockets will be at the back of the board or frame and would not appear to, or be seen by an observer of the 5 sign, and my invention may also, as will be understood, be employed for other purposes, and changes in and modifications of the construction herein described may be made, within the scope of the appended claims, 10 without departing from the spirit of my invention or sacrificing its advantages.

Although I have shown and described the use of only two circuit wires on which the lamp sockets are molded, my invention is 15 not limited to this idea and any number of circuit wires may be employed according to the use for which the device or apparatus, or the lamp sockets, are intended, or the method of such use.

20 Having fully described my invention, what I claim as new and desire to secure by Letters Patent, is:—

25 1. The method of making electric light streamers which consists in supporting electric circuit wires in parallel position providing said circuit wires at intervals with electric lamp socket fittings, supporting said

fittings in molds, and molding the socket bodies onto said circuit wires and fittings with the circuit wires passing laterally 30 through the heads of the socket bodies.

2. An electric light streamer device, comprising parallel circuit wires, electric lamp socket fittings connected with said wires at intervals and electric lamp socket bodies 35 molded onto said circuit wires and fittings, said wires passing transversely through the heads of said socket bodies.

3. An electric light streamer device, comprising parallel circuit wires and electric 40 lamp socket bodies molded on said wires at intervals, said wires passing transversely through the heads of said bodies and being in connection with electric lamp socket fittings within said bodies.

In testimony that I claim the foregoing as my invention I have signed my name in presence of the subscribing witnesses this 11th day of March 1915.

JOHN A. COVIT.
